DESK

James F. Dunn, Washington, D. C.

Application March 30, 1938, Serial No. 198,885

1 Claim. (Cl. 45—91)

(Granted under the act of March 3, 1883, as amended April 30, 1928; 370 O. G. 757)

The invention relates broadly to a desk and more particularly to a desk for the use of typists.

An object of the invention is to provide a desk that is sufficiently heavy and so balanced as to be non-vibrating when in use, although of small size.

Another object of the invention is to provide a desk that is compact in construction and arrangement of parts, easily portable, and one which occupies a minimum of floor space.

A further object of the invention is to provide a desk in which the compartments for holding supplies are within easy reach of a typist, thereby expediting the accomplishment of secretarial duties.

With the above and other objects in view, the invention consists in the construction, combination and arrangement of parts as will be hereinafter more fully described.

Reference is to be had to the accompanying drawings forming a part of this specification in which like reference characters indicate corresponding parts throughout the several views and in which:

Fig. 1 is a perspective view of a desk constructed in accordance with the present invention;

Fig. 2 is a section on the line 2—2 of Fig. 1 with the cover closed; and

Fig. 3 is a section on the line 3—3 of Fig. 1.

Referring more particularly to the drawings, 5 designates a desk as a whole constructed in accordance with my invention, and which is provided with conventional supporting legs 6. The desk is further provided with a hinged top cover 7 adapted to be supported, when in opened position, on a portion 8 of the desk. The cover, when open, as seen in Fig. 1, becomes a tray suitable for the reception of such papers as are ordinarily handled by a secretary. As may be seen in said figure, the tray is divided into two compartments by a partition 9 that is suitably pivoted in the opposite sides of the tray, one compartment of which may be used as an "incoming" basket, and

the other of which may be used as an "outgoing" basket. Although there is shown in the drawings but one partition, it will be understood a plurality of such partitions may be utilized, dividing the tray into several compartments. The front side of

the cover or tray is provided with a channel 10, the purpose of which will be explained hereinafter. The portion 8 serves as a convenient working place when the cover or tray of the desk is in a closed position.

To a partition 11 and end board 12 of the desk

(Fig. 2) are attached conventional guides 13 for drawers 14 for the reception of stationery, paper and other similar commodities, and just above the drawers there is conveniently placed a board to slide in the space 15 on the supports 16. A 5 drawer space is likewise provided at the other side of the desk between partition 17 and end board 18 to accommodate a drawer 19 slidable between guides 20. This drawer space, however, accommodates a drawer of considerable less 10 width than the drawers 14 and it extends from the bottom to the top of the body of the desk. This narrow drawer is designed to receive carbon paper or other such thin packaged material that can be set on its edge. A shelf 21 is hinged to one end of the desk, and, when in operative position, it is supported by a suitable bracket, shown in dotted lines in Fig. 1.

The body of the desk includes a well adapted to contain a typewriter mounted on a bottom 20 member 23 slidable between suitable guides 24 supported by members 25. The forward under side of the bottom member is undercut to form a shoulder 26 that abuts against the trim 27 to prevent the said member from being withdrawn 25 beyond a safe position. An envelop pocket 28 is provided on one wall of the well. The space behind the partition 29, forming the rear wall of the envelop pocket, and the partition 11 serves as a guideway 30 into which a sliding closure 31 30 rests when the desk is open for use.

This closure 31 is composed of a plurality of individual cylindrical members 32 banded together to form a flexible unit that is guided in its movement by a runway 33 between the trim 27 35 and the sliding bottom 23 and the guides 24. A suitable handle or finger piece 34 is attached to the closure for easy operation thereof, and also to provide a stop for the closure that it may not be so far seated in the space above referred to 40 that it may not be gripped with the fingers. A suitable guard 35 is placed over the guideway 30 to hold the closure from riding out of the guideway when it is rolled back to an opened position.

To close the desk, the top cover 7 is brought over the desk well and is automatically secured in closed position by a suitable spring catch, one part 36 of which is shown in Fig. 1, the co-acting member being suitably placed within the well. The closure 31 is then brought across the front 50 of the well to the position wherein it may be fastened by a suitable locking element shown at 37. When thus closed the desk cannot be opened by an unauthorized person without damage to the desk itself or locking element, because the spring 55

catch is in an inaccessible place behind the locked closure, which cannot be pulled out of position as its top edge is seated in the channel 10 in the top cover.

5 It will be understood that the above description and accompanying drawings comprehend only the general and preferred embodiment of my invention and that various changes in construction, proportion and arrangement of parts may 10 be made within the scope of the appended claim without sacrificing any of the advantages of my invention.

The invention described herein may be manufactured and/or used by or for the Government 15 of the United States of America for governmental purposes without the payment of any royalties thereon or therefor.

What I claim as new is:

In a desk, a central portion, a pedestal on either side of and extending to a higher altitude than the central portion to provide a well, the pedestals accommodating compartments, a sliding flexible member adapted to close the front of the well, a guide-way extending between the pedestals in which the said member operates, a hinged cover for the well adapted to provide a tray when opened, a channelway in the cover in which the flexible member rests when the cover and member are in closed positions, and pivotal means in the cover to divide it into compartments when opened. 5 10

JAMES F. DUNN. 15
